UNITED STATES PATENT OFFICE

JOSEPH GOULBOURN AND FRED RICKS, OF LEICESTER, ENGLAND, ASSIGNEES TO
UNITED SHOE MACHINERY CORPORATION, OF PATERSON, NEW JERSEY, A CORPORA-
TION OF NEW JERSEY

HONING DEVICE

Application filed December 27, 1926, Serial No. 157,353, and in Great Britain February 3, 1926.

This invention relates to abrading devices and is herein illustrated as embodied in a device for sharpening or honing the cutting edges of flat, rectangular knives having straight cutting edges.

While knives of the type above referred to are used in performing a number of various shoemaking operations, one of the most common uses of such knives is to be found in performing splitting or evening operations upon pieces of stock. The cutting edges of knives used in performing these splitting and evening operations are generally hollow ground, in a suitable grinding machine, and are subsequently submitted to a honing operation to impart to the knife a final and more perfect cutting edge.

With the foregoing in mind it is an object of the present invention to provide an improved device which may be operated to hone quickly and efficiently knives of the type referred to and by which the desired inclination of the ground face on the knife will be preserved independently of the skill of the operative in manipulating the honing stone.

In accordance with the above-stated object, a feature of the invention consists in the combination with a honing tool, a work holder and a clamp for maintaining work in the holder, of a gage movable between an operative position and an inoperative position, and a spring movable with the gage to either one side or the other of a dead-center position to maintain or lock the gage in either operative or inoperative position. The illustrated gage is an elongated member adapted to position a cutting blade or knife properly in the holder in operative relation to the honing tool by engagement with the cutting edge of the blade or knife.

It will be understood that the invention, which is herein illustrated as being embodied in a device for operating upon flat rectangular knives, is in no respect limited to the particular type of work to be operated upon other than may be determined from the scope of the appended claims.

The above and also other features of the invention, together with certain details of

construction and combination of parts will now be described with reference to the accompanying drawing and pointed out in the appended claims.

In the drawing,

Fig. 1 is a plan view of the knife grinding device showing a cutting blade supported within the work holder;

Fig. 2 is a side elevation of the device, as seen from the left of Fig. 1; and

Fig. 3 is a view in perspective of a splitting knife of the same type as that shown in Figs. 1 and 2.

As shown in the drawing, the device comprises a base or frame 10, substantially triangular in shape (Fig. 1) and provided upon its upper surface with a plurality of spaced seatings 12 upon which a blade 14 to be honed is clamped.

The knife or blade 14 (Fig. 3) is of flat rectangular shape and is of a type employed generally in splitting, or evening the thickness of, leather stock and shoe parts. The cutting edges of knives of this type are in the form of a straight line and are generally hollow ground.

For use in clamping the knife upon the seatings 12 there is provided a clamping lever 16 having an arm 18 extending forwardly above the top surface of the knife 14. The clamping lever 16 is pivotally and slidably mounted upon a horizontally extending stud 20, which stud is fixed in lugs 22 projecting upwardly from the frame 10. The lever 16 is provided in its rear extremity with a substantially vertical extending threaded hand screw 24, the lower end of which is arranged to engage the upper face of the frame when the lever 16 is at the inward end (Fig. 1) of its movement along the stud 20. By rotating the hand screw 24 when the lever 16 is in this position the lever may be swung about the stud to clamp the knife rigidly against the frame 10. When the screw 24 is rotated to release the knife the clamping lever 16 may be slid along the stud 20 until the screw and rearwardly extending portion of the lever 16 are clear of the edge of the frame 10 (Fig. 1) at which time the lever may be swung about its pivot to raise the forwardly

extending arm 18 out of engagement with the knife 14 to allow a knife upon which the honing operation has been completed to be removed and another un honed knife to be positioned with facility within the honing device.

The device is provided with means to assist in positioning the blade within the holder prior to applying the clamping pressure to the blade, and to this end there is provided 10 a pair of pins 26 which are vertically extending and arranged one at either side of the seatings 12. By means of the pins 26 the supported knife may be properly positioned transversely of the frame, and to assist in 15 positioning the blade longitudinally there is provided a gage 28 which is herein illustrated in the form of a pair of joined blocks extending laterally of the frame 10. As shown in Fig. 2 the gage 28 is mounted for movement 20 between an operative (full line) position and an inoperative (dotted line) position. A spring 30 extends between the frame and the gage 28 and, as the gage is moved from one of said positions to the other, the 25 spring moves with the gage, passing through a dead-center position, and then maintains or locks the gage in the desired position. In positioning a blade within the holder the gage 28 is moved to its operative position, as 30 shown in full lines in Fig. 2, and the blade is placed upon the seatings 12 between the positioning pins 26 with its cutting edge resting against the rear surface of the gage 28, and in this position the blade is clamped by means 35 of the lever 16 and hand screw 24. After the knife to be honed has been so positioned the gage 28 is swung outwardly and downwardly about its pivot into an inoperative position for the purpose of leaving the edge 40 of the knife clear and unobstructed for the honing operation.

At the rearward corner or apex of the triangular frame 10 there is formed a vertical boss 32 in which is rotatably mounted a spindle or supporting post 34 which may be adjusted vertically within the boss and is provided at its upper end with a rectangular portion 36 bored transversely to receive a pivot pin 38. On the pivot pin 38 and at each side 45 of the rectangular block 36 are located ears 40 extending downwardly from a substantially horizontally disposed sleeve bearing 42 in which is slidably and rotatably mounted a rod 44.

50 The rod 44 is provided with a band or casting 46 which is arranged to surround a discal honing stone 48. The stone 48 is cylindrical in shape and is somewhat thicker than the width of the band 46 so as to afford two opposed, easily accessible, honing faces which may be of different grades. It will be understood that the operative, by rotating the honing tool through 180° may, as desired, bring either of the different faces into honing relation with the cutting edge of a supported

knife. The stone 18 is maintained within the band 46 by means of screws 50 which pierce the band and abut a split ring 52 arranged to surround the honing stone. A handle 54 is secured to the band 46 and may be used in manipulating the honing tool.

The rod 44 carries at its rear end a collar 56, provided with a felt washer 58, which limits forward movement of the stone (longitudinally of the blade) to prevent the hone from slipping forwardly off the edge of the knife during the honing operation. A second felt washer 60 is located adjacent a boss formed on the band 46 and limits rearward longitudinal movement of the honing stone 75 during the honing operation. A plurality of pins 62 are located on the machine frame 80 symmetrically disposed with respect to the work holder and are for use in limiting movement of the honing stone transversely of the 85 work holder and of the supported blade during the honing operation.

In the use of the device, the edge of a clamped knife is located a substantial distance in front of the bearing 42 and the upward and forward inclination of the seatings 12 for the knife is such that the bevel of the knife and the face of the hone are substantially horizontal. It will be apparent that with this construction the honing stone may be freely moved by the operator in any direction over the edge of the knife and the honing may, therefore, be effected by movements similar to those used in hand honing, but that with this construction the angle of the knife edge remains unaltered since the pivot mounting of the stone while allowing the stone to be moved freely in any direction over the knife edge, prevents the stone from being tilted vertically across the edge of the knife.

Fixed to one side of the triangular frame 10 is a cup-shaped receptacle 64 (Fig. 2) which has on its upper face a recess or seating for the honing stone when it is not being used and this seating has in it a pad 66 of felt or other absorbent material upon which the stone rests. This pad 66 may be soaked in oil so that it will give up oil to the stone when the stone is placed on the pad. Thus the stone will always be kept properly lubricated and cleaned.

In the drawing a single bevel knife has been illustrated but it is pointed out that if it is desired to hone a double bevel knife the only change required from the construction shown is that the angle of the seatings 14 with the horizontal be altered in such a manner that the bevel surface of one side of the knife be located substantially horizontally when the knife is clamped to the seatings.

Having thus described our invention, what we claim as new and desire to secure by Letters Patent of the United States is:

1. In a honing and sharpening device, the combination with a work holder, a clamp for

- use in maintaining supported work within the holder, and a honing tool, of a movable gage between an operative and inoperative position for use in positioning properly 5 blades within the holder and a spring, movable with the gage to either one side or the other of a dead-center position, to lock the gage in either operative position or inoperative position.
- 10 2. In a sharpening and honing device, a honing tool, a work holder comprising a plurality of spaced positioning pins adapted to engage the edge of the supported work properly to position the work transversely within the holder, a gage comprising an elongated member movable between an operative and an inoperative position properly to position the supported work longitudinally within the holder a spring, movable with the gage to 15 either one side or the other of a dead-center position, to lock the gage in either position and a co-operating clamp member for maintaining rigidly the blade within the holder after it has been properly positioned by said 20 pins and gage.
3. In a honing and sharpening device, the combination with a honing tool and a knife holder, of a gage comprising a movable elongated member, a pivot for the gage, a spring 25 connected to the gage, said spring passing by the pivot upon movement of the gage to maintain the gage in either one of two positions, one of said positions being an operative position against which the knife may be positioned and the other being an inoperative position away from the knife, and a co-operating clamp member for maintaining rigidly the knife within the holder after it has been 30 positioned against the gage.
- 40 4. In testimony whereof we have signed our names to this specification.

JOSEPH GOULBOURN.
FRED RICKS.

CERTIFICATE OF CORRECTION

Patent No. 1,867,623.

July 19, 1932.

JOSEPH GOULDBOURN, ET AL.

It is hereby certified that error appears in the printed specification of the above numbered patent requiring correction as follows: Page 3, lines 3, and 4, claim 1, strike out the words "between an operative and inoperative position"; and that the said Letters Patent should be read with this correction therein that the same may conform to the record of the case in the Patent Office.

Signed and sealed this 23rd day of May, A. D. 1933.

M. J. Moore.

(Seal)

Acting Commissioner of Patents.
